(57) **CLAIM**

The ornamental design for a computer screen with a graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front, top, and right side perspective view of a first embodiment of a computer screen with a graphical user interface showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof.

FIG. 8 is a front, top, and right side perspective view of a second embodiment of a computer screen with a graphical user interface showing the new design.

FIG. 9 is a front elevational view thereof.

FIG. 10 is a rear elevational view thereof.

FIG. 11 is a top plan view thereof.

FIG. 12 is a bottom plan view thereof.

FIG. 13 is a right side elevational view thereof.

FIG. 14 is a left side elevational view thereof.

FIG. 15 is a front, top, and right side perspective view of a third embodiment of a computer screen with a graphical user interface showing the new design.

FIG. 16 is a front elevational view thereof.

FIG. 17 is a rear elevational view thereof.

FIG. 18 is a top plan view thereof.

FIG. 19 is a bottom plan view thereof.

FIG. 20 is a right side elevational view thereof; and,

FIG. 21 is a left side elevational view thereof.

The shades of grey in the third embodiment represent a contrasting appearance within the graphical user interface.
